UNITED STATES PATENT OFFICE.

JOSEPH URBANEK, OF CHICAGO, ILLINOIS.

DESIGN FOR A MIRROR AND PICTURE FRAME.

61,127.

Specification for Design.

Patented June 20, 1922.

Application filed April 6, 1922. Serial No. 1,561. Term of patent 14 years.

To all whom it may concern:

Be it known that I, JOSEPH URBANEK, a citizen of Poland, residing at Chicago, in the county of Cook and State of Illinois, have invented a new, original, and ornamental Design for a Mirror and Picture Frame, of which the following is a specification, reference being had to the accompanying drawing, forming part thereof.

The figure is a front elevational view of a mirror and picture frame, showing my new design.

I claim:

The ornamental design for a mirror and picture frame, as shown.

JOSEPH URBANEK.
